UNITED STATES PATENT OFFICE.

WILFRED B. GODDARD, OF PALO ALTO, CALIFORNIA.

SWITCHING MECHANISM FOR LAMP SOCKETS.

Application filed March 10, 1921. Serial No. 451,829.

To all whom it may concern:

Be it known that I, WILFRED B. GODDARD, a citizen of the United States, residing at Palo Alto, in the county of Santa Clara and State of California, have invented new and useful Improvements in Switching Mechanism for Lamp Sockets, of which the following is a specification.

The invention relates to improvements in 10 electrical lamp sockets, and more particularly to a type of the same involving a switching mechanism for controlling the lighting of the lamp carried by the lamp socket.

15 The primary object of the invention is to provide for a construction of the character mentioned and one of an extremely simplified form and arrangement of parts as to greatly facilitate the connecting of the 20 lamp socket onto an electrical circuit, and to otherwise reduce to a minimum the time required for such purpose.

Another object of the invention is to provide for a comparatively inexpensive construction of the type set forth, and one in 25 which the electrical current conducting parts of the lamp socket and the switching mechanism, in its entirety, may be readily and quickly assembled, positioned within 30 the socket, or removed therefrom, as the case may be, without the usual trouble obtaining in the ordinary or known types of the same.

A further object of the invention is to 35 provide for a device of the class described, and one in which the several electrical conducting parts of the lamp socket and the conducting, as well as the non-conducting parts of the switching mechanism, may be independently removed from position within 40 the lamp socket for the purpose of replacing the parts when desired, as when the same have been damaged, or otherwise unfit for further use.

A still further object of the invention is 45 to provide a lamp socket construction of the kind specified, and one wherein a pull chain switch operating means may be substituted in lieu of the push button type of such operating means, or vice versa, without any 50 change or modification whatever in the interior construction thereof, thus adapting the socket to universal use, and rendering it unnecessary to manufacture several forms of sockets one for each form of operating 55 means.

With the foregoing and other objects in

view, the invention resides in the certain novel and useful construction and arrangement of parts as will be hereinafter more fully described, set forth in the appended claims, and illustrated in the accompanying drawing, in which:

Figure 1 is a perspective view of the completed lamp socket, ready for use,

Figure 2 is a plan view of one section or part of the lamp socket with certain of its parts in cross-section, and showing the manner of arrangement of all of the parts thereof and of the switching mechanism therein,

Figure 3 is an edge view of the ratchet contact wheel of the switching mechanism,

Figure 4 is a detail view of the pawl and ratchet mechanism in one position of its operation,

Figure 5 is a view similar to that of 75 Figure 4 showing the pawl and ratchet mechanism in another position of its operation,

Figure 6 is a detail view of a modified 80 form of operating means for the pawl and ratchet mechanism, and

Figure 7 is a detail section on the line 7—7 of Figure 1.

Referring to the accompanying drawings, in which similar characters of reference 85 designate corresponding parts in the several views thereof, the numerals 10 and 11 indicate similarly formed, longitudinally split sections or parts of a lamp socket, the same being made of an insulating material, such as porcelain or the like. Each section has its opposed flat face formed with lower semi-circular threaded portions and upper recessed portions for the reception of the current conducting metallic parts and the parts of the switch mechanism to be enclosed between the sections, when properly assembled. The two sections 10 and 11 provide a substantially cylindrical body, when assembled, and have their upper ends round- 90 off, in the manner of and after the general form of ordinary types of lamp sockets. Extending vertically and medially of the outer surfaces of the sections 10 and 11 are 95 grooves which are adapted to receive the legs 13 of a substantially inverted U-shaped member 12, the same being made preferably of spring metal of sufficient resiliency to snugly engage in the grooves and to securely retain the sections 10 and 11 together, and against all possible separation 100 during the ordinary use of the lamp socket.

110

The grooves of the sections 10 and 11 terminate at opposite sides of a circular opening 14, formed at the rounded end portions of the sections, and which communicates with the interior of the upper recessed portions of the latter, and also registers with a corresponding opening formed in the connected portion of the U-shaped section clamping member 12. The grooves in each of the sections are preferably provided with suitable recesses 15' adjacent their lower ends for the reception of the spring tongues 15, which are struck out from the legs 13 and which cooperate with the recesses to further prevent the accidental separation of the parts of the lamp socket during the ordinary use of the same.

To admit of the use of unmodified or ordinary forms of threaded lamp bases with the lamp socket thus provided, the threaded portions of the sections 10 and 11 form a circular socket for the reception of the threaded lamp base, and current is transmitted to such lamp base through the medium of the spring contact fingers or arms 16 and 17, the finger or arm 16 lying in an annular groove formed in the wall of one of the sections and connecting with a vertically extending portion 18 which lies in a vertically extending groove in the wall of the section and projects into the recessed portion of the socket, while the finger or arm 17 is disposed medially of the upper end of the circular socket opening and has an upwardly extending portion 19 projecting into the upper recessed portion of the lamp socket. When a lamp base is screwed into the circular opening, the spring contact arm 16 will be engaged by the threaded metallic shell of the base and the spring contact arm 17 by the metallic end terminal of the latter, as usual.

The switching mechanism comprises a ratchet wheel 20, of an insulating material such as porcelain, having a toothed periphery 21, and a hub portion 22 extending to one side and having its outer face provided with a series of teeth 23, four of the latter being shown in the present instance. As shown, all of the teeth 23 are provided with metallic facings 24 each unconnected electrically one from the other. The ratchet wheel is provided with trunnions 25 by means of which the same is journaled in suitable aligning recesses in the opposed faces of the sections 10 and 11 of the lamp socket. Associated with the arm 18 of the spring contact 16 is a spring contact finger 26, which extends transversely of the socket and has its free end contacting the toothed surface of the hub portion of the ratchet wheel 20, and extending parallel to this finger 26, is a second spring finger 27, having its free end also contacting the toothed surface of the hub portion of the ratchet

wheel 20. The spring contact finger 27 has its fixed end formed with or otherwise secured to a contact strip 28 which, in turn, is secured in a groove or recess formed in the wall of one of the sections 10 and 11, and with its binding post 29, forms one of the terminals of the circuit to which the lamp socket may be attached. The arm 19 of the contact arm or finger 17 is also provided with a binding post 30 and forms the other terminal of the circuit to which the lamp socket may be attached, a two conductor lead (not shown) being passed into the opening 14 of the lamp socket, and having its conductors connecting the binding posts 29 and 30 for the purpose of introducing current to the parts indicated as conducting elements leading to and contacting the lamp base, when the same is threaded into the circular opening or socket.

For manipulating the ratchet wheel 20, a spring pawl 31, is provided, and, as shown, comprises a length of spring metal bent upon itself and having its lower portion bent to form a pawl tooth 32, which is of a shape to engage the teeth 21 of the ratchet wheel 20, in one direction of its movement and to ride over the teeth 21 in the other direction of its movement.

In the preferred form of the device, the pawl 31 projects inwardly from the end of an operating rod 33 which is slidably mounted in an opening formed in the end wall of an outwardly extending flared guide 34. This guide 34 is supported, in line with a channel 35 formed between the two sections 10 and 11 of the lamp socket, from an arm 36 curving downwardly over the line of connection between the sections 10 and 11, from the medial point of the clamping member 12 with which it is formed or attached. The guide 34 is preferably in the form of an outwardly flared tube, and has its inner end threaded into a threaded opening formed in the depending arm 36. Supported on the rod 33 is a coiled spring 37 which has one end abutting the inner end of the guide 34 and the other end abutting an angular shoulder 38 formed at the point of connection of the pawl 31 with the rod 33. For actuating the pawl 31 to impart rotary movement to the ratchet wheel 20, a pull chain 39 is attached to the outer end of the rod 33 and depends from the flared end of the guide 34. A spring finger 40 is secured between the sections 10 and 11 of the lamp socket and has its free end in the path of the teeth 21 of the ratchet wheel 20, and in a direction to allow the rotation of the latter only in the direction of the pull of the pawl through the medium of its operating rod and chain, the spring 37 being arranged to hold the latter in position for the rotation of the ratchet wheel in the proper direction.

With the lamp socket sections 10 and 11

formed as stated, and the metallic conducting and contact parts and the switch mechanism assembled and secured in position on one of the sections, the lead (not shown) 5 from the circuit is laid in the opening 14 and its conductors connected to the binding posts 29 and 30, after which, the other section is placed in position with its corresponding grooves, channels and recesses 10 engaging over the projecting portions of the parts of the conducting and contacting members and switch mechanism, and the clamping member 12 snapped into the grooves formed in the outer faces of the sections 10 and 11, the same having been 15 threaded onto the lead before the connecting of the conductors thereof with the binding posts 29 and 30, as aforesaid. The socket is now ready for the screwing of a lamp 20 (not shown) into the socket proper. With both of the contact fingers 26 and 27 engaged 25 on a single metallic face 24 of one of the teeth 23, current will flow from binding post 29, strip 28, contact finger 27, metallic face 24 engaged by contact fingers 26 and 27, contact finger 26, conductor 18, spring contact 16, the lamp base (not shown) the spring contact 17, the arm 19 to the binding post 30.

30 In the manipulation of the switch mechanism, and with both contact fingers 26 and 27 separated by the rise of one of the teeth 23 of the ratchet wheel 20, current is "off" from the socket and lamp. The first pull 35 on the chain 39 moves the pawl tooth 32 and one tooth 21, of the ratchet wheel 20 forward, tensioning the spring 37 which returns the pawl freely over and into engagement with the next succeeding tooth 21, 40 the spring pawl or dog 40 acting to prevent the rotation of the ratchet wheel 20 backwardly with the return movement of the pawl 31. If the contact finger 27 is on one tooth and the contact fingers 26 is 45 on another tooth, the circuit to the lamp is broken, and the movement of the ratchet the distance of one of the teeth 21 will bring both of the fingers 26 and 27 onto one tooth 23 and its face plate 24, and a 50 subsequent pull on the chain will move the ratchet wheel 20 another tooth length 21, and the circuit will be again broken by reason of the spring arm 26 dropping onto a succeeding tooth 23 and its face or contact plate 24, while the finger 27 will only move to the higher part of the tooth on which both fingers previously rested for the completion of the circuit. Consequently, during one revolution of the ratchet wheel 55 20, the circuit will be completed and broken four times each.

60 In the modified form of operating means as shown in Figure 6, in lieu of the pull chain 39 of the preferred form of the invention, a push button 41 is formed at the

outer projecting end of the operating rod 42, and in lieu of the coiled spring 37, a coiled spring 43 is interposed between the push button 41 and the inner end of the guide tube 34, so that its action is reversed 70 to that of the spring 37, in that the pawl 32 is held in its forward or inoperative position, and the spring 43 is compressed by a push on the button 41 and the pawl 32 moved rearwardly to operative position, 75 where it engages the nearest tooth 21 and under expansion of the spring 43 rotates the ratchet wheel 20 in the same direction as in the direct pull of the chain 39 in the first instance. 80

It is to be noted of the socket construction provided for herein, that the same is readily adaptable for universal use, i. e., either as a keyless socket, as by dispensing with both the pull chain and push button switch operating means, and turning the switch to "on" position; as a pull chain switch operating type; and as a push button type; the pull chain means and the push button means being interchangeable 85 one with the other without any change in the construction of the socket or modification of the parts thereof, the same being accomplished by simply unscrewing the flared guide 34, in either instance, and withdrawing the spring pawl through the channel 35, and the opening at the inner end of the said flared guide. 90

From the foregoing, it will be readily obvious that the invention provides for a lamp socket of a longitudinally split form such as admits of the quick assembling of the parts of the switch mechanism, the conductors and contacts, etc., together and in 100 operative position on one of the sections thereof; of extreme ease and rapidity in connecting the lamp socket section onto the terminals of the circuit; and of the quick positioning of the second section in 105 position on the first section and the snapping of the clamping member or yoke into the locking grooves for completing the lamp socket, all of which tends to greatly lessen the time required in the matter of installation of lighting systems and consequently 110 effects a marked saving in expenses or cost of such installation. This construction and arrangement of parts also admits of the same being replaced when damaged or worn out without necessitating the replacement of the lamp socket as a whole. 115

It is well understood that various changes in detail of construction, form and arrangement of the several parts may be resorted to without departing from the spirit 120 and scope of the invention.

Having thus fully described my invention, I claim:

1. In an electric switch, a pair of contact terminals for engagement with lamp 130

- contacts, a ratchet wheel of insulation material having peripheral feed teeth and also having a series of ratchet-tooth-shaped conducting surfaces, a pair of spaced contacts 5 for cooperation with the said conducting surfaces of the ratchet wheel, one of said spaced contacts being connected with one of said lamp terminal contacts and the other of said spaced contacts being adapted for 10 connection with a line conductor, said spaced contacts being so arranged with relation to each other and to the conducting surfaces of the ratchet wheel as to simultaneously engage one conducting surface of teeth of the ratchet wheel on one period of movement of said wheel and to separately engage adjacent conducting surfaces of teeth of the ratchet wheel on the next periodic movement of said wheel, and so on alternately throughout the 15 20 series of conducting surfaces in the revolution of the wheel, and means for intermittently actuating the ratchet wheel.
2. In an electric switch, a pair of contact terminals for engagement with the terminals 25 of a lamp base, a ratchet wheel formed of insulation material and having peripheral teeth and also having a series of conducting surfaces, a pair of spaced contacts for cooperation with the conducting surfaces of the ratchet wheel, one of said spaced contacts being connected with one of said lamp terminal contacts and the other of said spaced contacts adapted for connection with a line conductor, said contacts being so spaced as 30 35 to alternately engage the same and different conducting surfaces of the teeth of the ratchet wheel on successive periodic motions of the latter, means engageable with the feed teeth of the ratchet wheel for transmitting working motion to the ratchet wheel 40 for successive current making and breaking actions, and means for holding said ratchet wheel against retrograde rotation.
3. In an electric switch, a pair of lamp 45 terminal contacts, a ratchet wheel formed of insulation material and having peripheral feed teeth and also having a series of conducting surfaces, a pair of spaced contacts for cooperation with the teeth conducting 50 55 surfaces of the ratchet wheel, one of said spaced contacts being connected with one of said lamp terminal contacts and the other of said spaced contacts being adapted for connection with a line conductor, said contacts being arranged to alternately engage the same and different conducting surfaces of the teeth of the ratchet wheel on successive movements of said wheel, a longitudinally 60 65 movable pawl engageable with the feed teeth for turning the ratchet wheel a distance of one tooth on each working motion thereof, means for manually moving said pawl in one direction, and means for automatically moving the pawl in the reverse direction.
4. In an electric switch, a pair of lamp 65 70 75 80 85 90 95 100 105 110 115 120 125 130 terminal contacts, a ratchet wheel formed of insulation material and having a series of peripheral feed teeth and a series of ratchet-shaped contact members on one side thereof, said contact members being provided with conducting surfaces, a pair of spaced contacts for cooperation with the conducting surfaces of the ratchet wheel, one of said spaced contacts being connected with one of said lamp terminal contacts and the other of said spaced contacts being adapted for connection with a line conductor, said spaced contacts being arranged to simultaneously and separately engage the same and adjacent conducting surfaces of the ratchet wheel on successive periodic motions of said wheel to alternately make and break a circuit, and means for engagement with the peripheral teeth of the ratchet wheel for transmitting periodic movements thereto.
5. In an electric switch, a rotary switch member having peripheral ratchet feed teeth and having upon one of its lateral faces a series of relatively electric insulated conducting surfaces, means engageable with the peripheral teeth of the ratchet wheel for turning said wheel a distance of a feed tooth on each motion thereof, and a pair of spaced contacts for cooperation with the lateral conducting surfaces of the ratchet wheel, said teeth being arranged to simultaneously engage a circuit conducting surface on a determined movement of the ratchet wheel and to engage different lateral conducting surfaces on the next movement of the ratchet wheel, and to operate alternately in this manner for circuit make and break action in the rotation of the ratchet wheel.
6. In an electric switch, a ratchet wheel having peripheral feed teeth and ratchet-shaped conducting surfaces on one of its sides, said surfaces being electrically insulated from each other, a reciprocable pawl for engagement with the peripheral ratchet teeth for imparting intermittent feed motion to said ratchet wheel, and spaced contacts forming part of an electric circuit for cooperation with the lateral conducting surfaces of the ratchet wheel, said contacts being arranged to alternately engage the same and adjacent conducting surfaces of the ratchet wheel on successive intermittent motions of the latter.
7. In an electric switch, a casing comprising two longitudinally separable sections and having at one end an opening for passage of a lead thereinto and formed at diametrically opposite sides thereof with longitudinal grooves and locking recesses, switch mechanism carried by said casing, and a spring fastener for holding the casing sections assembled, said fastener having a head portion to engage said end of the casing and provided with an opening registering with the lead opening therein, and provided with

resilient arms fitting in said grooves and having locking projections to engage the locking recesses.

8. In an electric switch, a casing comprising a pair of separable sections and having at one end an opening for entrance of a lead and in one of its sides an opening for passage of a switch actuating device, said casing sections being also provided at diametrically opposite sides with longitudinal grooves and locking recesses, switch mechanism in said casing, an actuating device for said switch mechanism including a part extending externally through said side opening in the casing, and a spring fastener for holding the casing sections assembled, said fastener having a head portion to embrace the said end of the casing and formed with an opening to register with the lead opening therein, and provided with resilient arms to engage the said longitudinal grooves and spring tongues carried by said arms to interlock with said locking recesses.
9. In an electric switch, a casing comprising two longitudinally separable sections and having at one end a lead opening and in one side an opening for passage of a part of a switch mechanism actuating device, said casing sections being also provided at opposite sides with longitudinal grooves and locking recesses, switch mechanism within said casing, a spring fastener for holding the casing sections assembled, said fastener comprising a head portion to engage the aforementioned end of the casing and having an opening to register with the lead

opening therein and provided with spring arms for engagement with said grooves, and said arms having locking tongues to engage the locking recesses, and said fastener having a third arm provided with an opening registering with the side opening in the casing, a guide engaging said opening in said third arm, and a switch actuating device in the casing having a part extending through said guide.

10. In an electric switch, a two-part longitudinally separable casing, said casing having an end opening for passage of a lead and a side opening, and formed in its sides with longitudinal grooves and locking recesses intersecting said grooves, a spring fastener having a head portion engaging said end of the casing and provided with an opening registering with the lead opening therein, and having spring arms engaging said longitudinal grooves and provided with tongues to interlock with the locking recesses, said fastener also having a third arm overlying the side opening in the casing and provided with an opening registering therewith, a guide detachably fitted in the opening in said third arm, switch mechanism within the casing, and a switch actuating device having a part movable through said guide, said actuating device being adapted for removal as a whole through the opening in the side arm when said guide is detached from said opening.

In testimony whereof I affix my signature.

WILFRED B. GODDARD.
